POSITIVE BUOYANCY PRIME MOVER
Emil Baumgartner, 125 Woodfield Road,
West Hempstead, N.Y.
Filed Apr. 8, 1963, Ser. No. 271,345
3 Claims. (Cl. 60—22)

This invention relates to prime movers and particularly to such devices deriving their motive power from the positive buoyancy of a body immersed in a fluid medium.

The need has long existed for efficient prime movers which are not dependent upon combustible fuels for their operation. Such devices would have wide application in a variety of uses. One well known form of prime mover is the water wheel. For efficient operation, the water wheel requires a large head of water, and this frequently presents a serious problem. Preferably, the water wheel should be in close proximity to the water source and, in addition, a constant flow of water must be maintained.

The present invention derives its power from that inherent property in a body, buoyancy, that permits it to float to the surface of a liquid medium. Therefore, it may be said that the present invention utilizes the upward force exerted on an immersed body by the supporting fluid medium. This upward force, independent of the weight of the immersed body and dependent upon the volume of fluid displaced by the body, is converted to a rotary motion by the structure of the present invention whereby it may be utilized by a variety of devices coupled thereto.

A feature of this invention is that it converts the buoyant property of a body submerged in fluid to usable power.

Another feature is that the fluid may be an inexpensive one such as water.

An additional feature is that the present invention merely requires an initial input of compressed gas, such as air, and conventional means to seal the container to prevent fluid and gas leaks.

Still another feature of the invention is that it is basically rugged and capable of operation with a minimum of maintenance.

A further feature of the present invention is the provision of a positive buoyancy prime mover whose rotational speed is self-regulating.

Another feature of the invention is the provision of speed regulating means.

These and other features and advantages of the present invention will, in part, be pointed out with particularity and will, in part, become apparent from the following description, taken in conjunction with the drawing appended hereto.

In the various figures of the drawing like reference characters designate like parts.

In the drawing:

FIG. 1A schematically illustrates the operating principles of the present invention.

FIG. 1B schematically illustrates the self-regulating principles of the present invention.

FIG. 2 is an elevational side view in section of one embodiment of the present invention.

FIG. 3 is a sectional view taken along line 3—3 of FIG. 2.

FIG. 4 illustrates an arrangement of a plurality of devices constructed in accordance with the features of FIG. 2.

FIG. 5 is a view similar to FIG. 4 and illustrates an alternative arrangement.

FIG. 6 is another view similar to FIG. 4 and illustrates still another alternative arrangement.

2

FIG. 7 is a side elevational view of the embodiment of FIG. 6.

Referring now to FIGS. 1A and 1B, there is shown the present invention in schematic form. As is well known, positive buoyancy exists when the weight of a body submerged in a fluid is less than the weight of the volume of fluid displaced by the body. For purposes of illustration, a series of hollow float members 12a—12L are linked to a common axle 14 by means of rigid spokes 16. Approximately three-quarters of the apparatus is submerged in a fluid 18, such as water. Since buoyancy is a function of the weight of the fluid displaced, it is envisioned within the scope of the present invention to use fluids other than water. The greater the fluid density, the greater will be the power output. It will be seen then that mercury with a density of 13.60 gm./cm.³ (848.64 lbs./ft.³), as opposed to water having a density of 1.00 gm./cm.³ (62.4 lbs./ft.³), will be even more effective. Other fluids, such as chloroform (density 1.53), glycerine (density 1.26), with densities in between the two extremes of water and mercury, may satisfactorily be used. It is presently contemplated to use chloroform, because of its volatility, in only small sealed instruments.

Floats 12a—12e in quadrants III and IV will, because of their buoyant property, tend to float upwardly to the top of the fluid medium. Since the floats are rigidly secured to axle 14 by means of radial spokes 16, the axle will be rotated clockwise, as shown by the arrow in FIG. 1A. Rotation of the axle will cause rigidly secured floats 12g—12k in quadrants I and II to move clockwise. Floats 12g—12k pass through a plenum formed by shroud 20 which, for purposes of explanation, is to be accepted as being maintained fluid-free by having compressed air pumped into it through conduit 22. An externally located compressor supplies conduit 22 through a constant pressure control valve. From the foregoing description, it is seen that successive floats are passed from the fluid-free air lock, wherein there are no upward buoyant forces exerted, into the fluid medium wherein the buoyant forces set up clockwise moments about a central axis.

A practical embodiment of the invention is shown in FIG. 2 and FIG. 3. The apparatus is contained within housing 30 having a removable cover 32 affixed thereto by means of fasteners 34. The housing and cover are provided with flanges 30a and 32a, respectively, between which is positioned a gasket 36 for the purpose of sealing the interior of the housing which is partially filled with liquid 38. Transverse shaft 40 is rotatably journaled in bearings 42 affixed to the side walls of housing 30 and has rigidly secured thereto a pair of spaced support members 44. Equally spaced support rollers 46a, 46b and 46c are rotatably journaled at their end portions in support members 44 and frictionally engage the inner diameter of a hollow buoyancy ring 50.

Ring 50 is circular in shape and hollow in cross section. As will be explained hereinafter, the side walls and inner and outer diameter faces may be relatively thin. Compartments 52 are formed inside and are interconnected by means of small apertures 54 in radial walls 56. As previously stated, buoyancy is independent of the weight of the immersed body but dependent upon the volume of displaced fluid. Therefore, ring 50 could conceivably be made of almost any formable material, the prime limitations being the environment in which it is disposed. However, in order to minimize the inertial properties the buoyancy would have to overcome, the embodiments herein illustrated show a relatively thin walled hollow wheel. Valve means 58 is provided flush with the side wall so that the compartments may be filled with a gas. This will prevent the walls from collapsing and permit the

ring to withstand the pressures external thereto attendant with submersion in the liquid medium.

As ring 50 rotates about support rollers 46a, 46b and 46c, it will frictionally drive the rollers. To facilitate this action and also to guide the ring in a true path, the rollers are provided with flanges 60 which straddle the inner and outer ring walls. It should be understood that separate rollers having integral pulleys free to rotate on shafts 46 may be substituted. Pulleys 62a and 62b in this embodiment are secured to shafts 46a and 46b, respectively, and in combination with pulley 64, fixed to transverse shaft 40 intermediate members 44, transfer the rotation of the ring to the shaft by means of an endless belt 66 trained about all three pulleys.

Closely spaced about ring 50 is a plenum in the form of shroud 70 which is substantially semicircular in shape and conforms closely in cross section to the cross sectional configuration of ring 50 (FIG. 3). The shroud is secured to stepped down portions 44a of support members 44 as by welding. Conduit 72, communicating with the interior portion of shroud 70, maintains a supply of air in the shroud from an externally located compressor 74 the output of which is regulated by a constant pressure valve 76. As a further safeguard against admission of fluid into the plenum, sealing member 77 is provided about the immersed, open end of shroud 70. This does not impede the rotation of ring 50. It may be seen then that the air pressure within the shroud may readily be maintained at a substantially higher level than the fluid pressure within the housing. Thus the portion of the ring within the air lock is not subject to a buoyant motion. The portion of the ring outside the air lock is submerged in the fluid medium and exhibits buoyant characteristics causing each point on the ring to float upwardly thus turning the ring clockwise (FIG. 2) within the plenum and also about frictionally engaged rollers 46a and 46b. By varying the air pressure, fluid may be introduced into or displaced from the shroud and the speed of the rotation may be varied.

Ring 50 is well supported and runs concentrically with and in the same plane as shroud 70 by virtue of the three-point suspension provided by equally spaced rollers 46a, 46b, which were previously described, in combination with roller 46c rotatably journaled in an enlarged localized portion 78 of shroud 70.

The transverse shaft which is rotated by the drive system comprised of ring 50, rollers 46a and 46b together with belt 66, is provided with a gear train 80 comprising gear 82 pinned to shaft 40 to rotate therewith and mating gear 84 fixed to output shaft 86. Thus the buoyancy motion of ring 50 may be converted into a mechanical output. While the output motion is shown to be rotary, it is possible by the inclusion of suitable gearing, such as a rack and pinion arrangement, to produce a reciprocal linear motion, intermittent linear motion as well as oscillatory motion both linear and angular.

To control the rate of output, a conventional fly wheel governor 90 is secured to output shaft 86. Upon an increase in output shaft speed, fly wheel balls 92 adjustably secured to pivoted arms 94 are thrown outwardly by centrifugal force. This action causes hinged arms 96 to slide upwardly on shaft 86 and carry with it yoke member 98. The opposite end of yoke 98 is secured to a rack 100 which is guided in a vertical path by guide members 102, slidably positioned in ways 104 of rack 100. Guide members 102 are part of bracket 106 which is fixed to housing 30, as shown in FIG. 2. Rack 100 meshes with gear segment 108 which is secured to the peripheral, outside face of shroud 70. Any movement of the rack as caused by either an increase or decrease in the speed of output shaft 86 will cause an angular displacement of shroud 70. Since support members 44 are secured to shroud 70 at stepped down portions 44a, a displacement of the shroud will cause a comparable displacement of support rollers 46a, 46b and 46c, thus maintaining equally spaced three

point suspension of ring 50. This effect can be most readily visualized when the mechanical structure is viewed in conjunction with a diagrammatical illustration. Referring now to FIG. 1B wherein schematically shown shroud 20 (comparable to shroud 70 of FIG. 2 and FIG. 3) is angularly displaced corresponding to the action occurring when float members 12 (comparable to ring 50 of FIG. 2 and FIG. 3) are rotated at greater than the desired speed, it will be noted that a float in quadrant II will exhibit positive buoyancy in a counterclockwise direction. This will, in effect, work oppositely to the buoyant force of the remainder of the immersed floats and therefore cause the ring and hence the output shaft and governor to slow down to the desired speed. The desired speed control may be obtained by properly setting the governor in accordance with usual practice. A decrease in speed will cause an equal but opposite reaction and will be similarly self-regulating.

Referring once again to FIG. 2, output shaft 86 is journaled in coupling member 110 fixed in cover member 32. Coaxial drive shaft 86a is also journaled in member 110 which is preferably a fluid coupling capable of sealing and preserving the internal pressure of the apparatus. Thus shaft 86a, directly coupled to and governed by the rotational speed of ring 50, may be employed to drive a utilization device. Alternatively, a utilization device such as a generator 112 may be positioned inside the housing and coupled directly to shaft 86 by means of pulleys 114 and 116 about which is trained endless belt 118. To utilize this configuration, feed-through terminals 120 are provided in cover member 32 providing means for coupling the generator to an external utilization system. It should be noted that at any point where a member passes through either the housing or cover walls, suitable sealing means are provided so that internal pressures, particularly in the air lock, are maintained. Conventional reversing mechanisms, illustrated schematically at 122, may be employed in conjunction with drive shaft 86a so that the output may be either clockwise or counterclockwise and may be changed from one to the other according to specific applications.

FIG. 4, 5, 6 and 7 disclose further applications of the present invention. It should be understood that the operating principles are the same as described heretofore and for simplicity, certain elements have been omitted and the remainder shown in outline form. Like reference characters are utilized to denote similarly functioning parts.

In FIG. 4 there is shown a plurality of assemblies side by side on common transverse shaft 40. The assemblies are each comprised of a ring 50 supported on friction rollers 46 and an angularly displaceable shroud 70. Support members 44 carry the assemblies as well as gear train 80. A rack 100 is provided as means for speed control. Single output shaft 86, driven by the gear train will consequently be driven with increased power. Endless belts 66 transmit power from ring 50 to transverse shaft 40 as heretofore described.

FIG. 5 illustrates a tandem arrangement whereby each individual assembly comprised of a ring 50 and a shroud 70 is provided with its own transverse shaft 40. The several transverse shafts are coupled to each other by means of a series of pulleys 130 mounted thereon, said pulleys being interconnected by endless belt 132. A single output shaft (not shown) takes its power from the sum of the rotation forces of the individual assemblies.

The embodiment of FIG. 6 and FIG. 7 is in effect a combination of FIG. 4 and FIG. 5 wherein several assemblies are journaled about a single transverse shaft 40 and the housing 30' is constructed so as to accommodate several transverse shafts 40, one behind the other, said shafts being mechanically coupled as indicated by phantom lines 140. Gear trains 142 are adapted to drive propulsion means, such as propellers 144, so that this 75 may be a water-borne vehicle. In this embodiment then,

bulkhead 146 defines a substantially fluid filled chamber 148 which contains the operating mechanism of the present invention. Compressor C having suitable valve control pressurizes shrouds 70. As in the previous embodiments, a plurality of rings 50 and shrouds 70 are employed to drive transverse shafts 40. Similarly, speed control means, comprised of racks 100 and gear segments 108, are affixed to shrouds 70. The speed control means are suitably linked to each other and have a single control such as wheel 150 which moves the racks up and down through lead screw 152. With this arrangement, even if body 30' is at an angle with respect to the horizon, the shrouds may be adjusted for optimum performance.

The description set forth hereinabove illustrates the basic operating principles as well as several practical embodiments of the present invention. It will be seen that the apparatus is relatively simple to construct, operate and maintain. Means have been provided for easy adjustment which assures a steady predictable output. A range of power output may be obtained by a suitable choice of fluid mediums, as well as determination of the most advantageous size of components, the selection of which is dependent on the application.

There has been disclosed heretofore the best embodiment of the invention presently contemplated and it is to be understood that various changes and modifications may be made by those skilled in the art without departing from the spirit of the invention.

What is claimed is:

1. A prime mover comprising:
(A) a body of liquid;
(B) a buoyant ring member comprising a plurality of individual compartments sealed from the surround-

5

ing environment and having a density less than said liquid whereby the upward flotation of said chambers will cause said ring member to rotate about a substantially horizontal axis;

(a) said ring member being at least partially submerged in said liquid;

(C) speed control means comprising an angularly adjustable plenum chamber containing a gas, said chamber enveloping a portion of said ring extending from the surface of said liquid to the lowermost portion thereof and maintained fixed relative to said ring during constant speed rotation of said ring,

(a) said chamber being at least partially submerged in said liquid; and

(D) output means coupled to said ring member whereby, upon rotation of said ring member, a power output is obtained.

2. The apparatus of claim 1 including speed governing means coupled to said output means, said speed governing means being adapted to angularly adjust said plenum chamber with respect to said ring.

3. The apparatus of claim 1 including means to maintain the gas pressure within said plenum chamber at a constant level.
